COMBINATION BURIAL CASKET AND VAULT

Percy O. Johnson, Columbus, Ohio

Application June 8, 1950, Serial No. 166,807

3 Claims. (Cl. 27—6)

1 This invention relates to undertaking equipment and is particularly directed to a combined burial casket and grave vault. One of the objects of the invention is to provide a casket or grave vault which will be simple to manufacture, light in weight, will be moisture proof, in that it will prevent the entrance of water from the exterior, and will also prevent the escape of odors or other objectionable matter from the enclosure.

Another object is to provide a combination burial casket and grave vault composed mainly of two inter-fitting pieces neither of which contains any openings other than the open top or bottom of the relative pieces.

A still further object of the invention is to provide a device of the character mentioned in the preceding paragraph having a bottom section with a bottom wall and upstanding peripheral side walls and a top section having a top wall and depending peripheral side walls the latter being off-set so that when the top is disposed on the bottom section the side walls will extend downwardly on the outer sides of the walls of the base section to form in effect an air bell which will prevent water, which might accumulate in the grave, from rising inside of the top section to a height sufficient to flow over the upper edges of the side walls of the bottom section.

It is a further object of the invention to provide the walls of the sections mentioned in the preceding paragraph with inter-engaging seats and to locate a mastic composition between such seats to seal the parts and thus prevent the entrance or exit of all fluids or gases into or from the casket.

It is also an object of the invention to provide a casket and vault combined, which will be suitable for formation by die casting methods and to provide convenient means for locking the top and bottom sections of the device together to prevent accidental separation thereof, yet permitting removal of the top from the bottom section when desired.

Another object of the invention is to provide a convenient means for securing the lining of the casket to the bottom section to facilitate the fabrication of the device.

Further objects and advantages of the present invention will be apparent from the following description, reference being had to the accompanying drawing wherein a preferred form of embodiment of the invention is clearly shown.

In the drawings:

Fig. 1 is a perspective view of a combination burial casket or vault formed in accordance with

65

An inspection of Figs. 2 and 3 will disclose the

present invention, the parts thereof being shown in assembled relationship, **2** is a vertical transverse sectional view taken through the combination casket and vault shown in Fig. 1.

3 is a detailed vertical sectional view taken through the side wall of the device on an enlarged scale.

4 is an elevational view of the inside of a side wall of the top section of the vault, this view being indicated by the line IV—IV of Fig. 3.

Referring more particularly to the drawings the combination casket and vault is indicated generally by the numeral **20**. This device includes a bottom section **21** and a top or cover section **22**. The bottom section includes a bottom wall **24** and a peripheral side wall **25**, which is integral with the bottom wall and extends completely around the same, wall **25** projecting in an upward direction.

It is one of the objects of this invention to provide a combination casket and vault which will be suitable for manufacture by die-casting methods, the connection therefore, between the bottom and side wall is rounded as at **26** and the bottom and side walls may be suitably reinforced where necessary by internal ribs **27**. It should be obvious that such ribs could be located exteriorly as well, if desired.

The bottom section **21** is, in this instance, provided with a plurality of bosses, or lugs **28**, on the outer sides of the side wall **25**, these lugs being disposed adjacent the lower portion of the side wall to prevent the depending walls **30** of the top section from engagement therewith when the top and bottom sections are assembled.

The lugs **28** are provided with openings **31** for receiving the ends of laterally projecting fingers **32** provided on a handle bar **33**, one of these bars being located on each side of the casket. It should be obvious that additional bars could be provided at the ends of the casket if desired. The outer ends of the fingers **32** may be deformed, or otherwise treated as indicated at **34**, to prevent the removal of the bars from the lugs.

It will be apparent that the casket may be elevated and transported by grasping the bars and applying a lifting force thereto. It will be noted that the fingers **32** are arranged beneath the lugs and have their ends projecting upwardly through the openings, the portions of the fingers below the lugs extending outwardly so that lifting force applied to the bars will be transmitted through the lugs to the side walls of the casket.

fact that the upper portion of the side wall 25 is thickened, as at 35, this thickened portion reinforcing the side wall at its upper edge and providing a seat 36 for the top section. This thickened portion terminates at its lower end in a downwardly facing shoulder 37, the purpose of which will be hereinafter set forth.

It will also be noted from Fig. 3 that the upper end of the side wall at the thickened portion is provided with inwardly extending prongs, or tines 38, these members being provided with relatively sharp points 40, so that wooden or similar strip 41 may be impaled thereon. In fabricating the casket the wood strip is alined with the upper edge of the side wall and pressed against the same to embed the prongs 38 therein. These prongs will maintain the position of the strip and prevent it from dropping downwardly into the casket. The strip 41 provides a convenient backing to which the casket lining, indicated by the numeral 42, may be secured, this lining being both cemented or glued and tacked in place on the strip. Suitable filling indicated by the numeral 43 may be placed in the casket before the lining is assembled therein.

The top section of the combined casket or vault includes a curved top wall 44 from the edges of which the side walls 30 depend. These side walls are off set to provide a peripheral downwardly facing shoulder 45 at the juncture between the side and top walls. This shoulder constitutes a seat for engagement with the seat 36 provided on the bottom section; a suitable mastic indicated by the numeral 46, is disposed between these seats before the top is applied to the bottom to seal the vault against the passage of fluids or liquids into or out of the same.

To prevent undesired separation of the top and bottom sections the former is provided adjacent the lower edges of the side walls with inwardly projecting bosses 47. These bosses have openings 48 formed therein to receive tongue like projections 50 formed on locking plates 51. These plates are of a width sufficient to permit the plates to rest on the upper surfaces of the lugs 47, the plates being loosely supported by such lugs and tending to rock inwardly away from the side walls of the top section. When the top section is applied to the bottom section these plates will be engaged by the side walls of the bottom section and moved outwardly until the shoulder 37 passes the upper ends of the plates after which the latter may swing inwardly beneath the shoulder and thus lock the sections against accidental separation. It will be obvious that if it is desired to separate the sections after they are once locked the plates may be engaged by the fingers or suitable tools and swung outwardly away from the shoulders 37 after which the top section may be elevated and removed from the bottom section. While the locking plates have been shown on the side walls, it should be obvious that they may also be applied to the end walls or to the end walls alone depending upon the desires of the manufacturer.

In some instances it is desirable, when a body has been laid out in a burial casket and is ex-

posed for inspection, to use a protective glass sealer or frame with a pane of plate glass to cover the open upper end of the casket. Such a glass sealer is generally quite heavy so to support the same the side walls of the bottom section 21 are provided adjacent their upper ends, with spaced lugs 52 which are integrally formed with the wall. These lugs are of sufficient size and strength to support the glass sealer which will be disposed on the wood strips extending around the upper edges of the side walls 25. These wood strips are formed with recesses to receive the lugs 52 when the strips are being put in place during the fabrication of the casket.

While I have shown and described the invention in one of its simplest forms it should be obvious that many minor changes may be made in the construction and relation of parts without departing from the spirit and scope of the invention as set forth in the following claims.

I claim:

1. In a burial casket, a body member having upstanding peripheral walls; a plurality of spaced lugs projecting inwardly from the upper portions of said walls; a plurality of sharp pointed prongs projecting inwardly from said walls; and tack receiving strips impaled on said prongs, said strips having recesses for receiving said lugs and being held thereon by said prongs.

2. In a burial casket, a body member having upstanding peripheral walls; a plurality of lugs projecting inwardly from the upper portions of said walls, said lugs being spaced longitudinally of said walls; a plurality of sharp pointed prongs projecting inwardly from said walls in spaced relation from said lugs; and tack receiving strips impaled on said prongs, said strips extending longitudinally of said walls and having recesses for receiving said lugs, said prongs retaining said strips on said lugs.

3. In a burial casket, a body member having upstanding peripheral walls; a plurality of lugs projecting in a substantially horizontal direction from said walls, said lugs being spaced longitudinally of said walls; a plurality of sharp pointed prongs projecting substantially parallel with but spaced from said prongs; and a tacking strip impaled on said prongs, said strip having openings for the slidable reception of said lugs.

PERCY O. JOHNSON.
